UNITED STATES PATENT OFFICE

148,380

DESIGN FOR A BABY CHAIR

Harvey V. Noel, Dayton, Ohio

Application August 13, 1946, Serial No. 132,464

Term of patent 3½ years

(Cl. D15—8)

To all whom it may concern:

Be it known that I, Harvey V. Noel, a citizen of the United States, residing at Dayton, in the county of Montgomery and State of Ohio, have invented a new, original, and ornamental Design for a Baby Chair, of which the following is a specification, reference being had to the accompanying drawing, forming a part thereof.

In the drawings,

I claim:

The ornamental design for a baby chair, as shown.

HARVEY V. NOEL.
